LUCIEN C. BABCOCK, OF NEW YORK, N. Y.

MACHINE FOR AUTOMATICALLY SEALING ENVELOPS.

SPECIFICATION forming part of Letters Patent No. 758,497, dated April 26, 1904.

Application filed June 18, 1903. Serial No. 162,088. (No model.)

To all whom it may concern:

Be it known that I, LUCIEN C. BABCOCK, a citizen of the United States, residing in the borough of Brooklyn, in the city and State of New York, have invented a new and Improved Machine for Automatically Sealing Envelops, of which the following is a specification.

Modern business has developed in many branches a necessity for not only sending out unsealed matter in the nature of circulars, but also for sending out through the mails large quantities of closed and sealed letters. With the labor of preparing and filling the envelopes this invention has nothing to do. Envelops having their flaps gummed in the ordinary process of manufacture and having been filled by hand or otherwise with the proper mailable matter and brought to this machine in piles, with the dry flaps lying down in the ordinary position on the back face of the envelop, are fed into the machine face downward and are carried forward one after another on an endless chain of platforms or carriers and in their passage on the top of such chain or train of carriers the flap is lifted, thus unfolding the envelop. In this condition the gummed face of the flap is dampened, and at a little later period the body is lifted up on edge, which has the effect to close the envelop, and after pressing the body and the flap together in that position the envelop is discharged properly sealed.

I have devised important improvements in details, especially for applying the moisture by a roller and maintaining and controlling the degree of wetness on such roller and a provision for wiping the surfaces during the return movement.

The following is a description of what I consider the best means of carrying out the invention.

The accompanying drawings form a part of this specification.

Figure 1 is a plan view of the machine. Fig. 2 is a corresponding vertical section with the tank and feed-roller omitted. Fig. 3 is a vertical section on the line 3-3 in Fig. 1 seen from the left, the water-tank, feeding-roller, and wetting-roller in elevation. Fig. 4 is a vertical transverse section of a portion, on a

large scale, showing the spring side piece in an inoperative position. Fig. 5 represents the same parts with the side piece in position for holding the flap of the envelop erect. Fig. 6 is a vertical section of a portion on the line 55 6-6 in Fig. 1, and Fig. 7 is a side elevation showing the outer faces of one set of the side pieces.

Similar letters of reference indicate corresponding parts in all the figures where they appear.

A is the framework, of cast-iron or other suitable material, and B a horizontal transverse shaft capable of being turned in bearings therein.

B' is a cylindrical pulley fixed on the shaft and revolving therewith by the aid of any suitable means, as a hand-crank B''. Near the other end of the machine is a similar pulley C', carried on a shaft C, turning also in fixed supports. D is an endless belt, of canvas or other flexible material, stretched around such pulleys. The upper stretch of this belt is held up, so as to resist gravity and all ordinary forces, by a plane table A', extending across the machine in the position represented.

E E, &c., are short rigid platforms (I have in my experiments used hardwood) secured to the belt D by screws E' and traveling around therewith. They are aggregated in sets. I have shown three in each set. The outer faces of these platforms, the upper faces when they are being worked in the upper part of their course, are plane except as follows: One end of each platform is reduced in thickness. The transition being made by a sudden offset (marked e) performs an important function, as will presently appear. There is a shallow groove e', extending transversely across the upper surface of each near the other end, adapted to receive the point of a fixed plow A¹⁰ to lift up anything carried on the platform.

To the thin end of each platform E at just the proper distance from the offset e is connected by two small hinges F a side piece G, adapted to turn to a considerable extent on such hinges. It is important that these side pieces shall be strong and present each a fair face toward the envelops which they are to

treat, so that they may transmit the pressure fairly to the envelop during the treatment. It is also important that each side piece shall be elastic, so as to allow for variations in the thickness of the envelop, and especially in the thickness of the contents. I have shown these side pieces as formed of thin metal, each nearly folded upon itself along the upper edge. The side pieces are so proportioned and set that when they are in the inclined position their edges G^2 lie a little above the level of the tops of the platforms E.

A^3 is a guide which may, as shown, be made of stout wire inserted in the main framing A. The duty of these parts is to hold down the main body of the envelop when a force is applied, as will presently appear, tending to bend the whole envelop. By holding down the body of the envelop by means of this guide A^3 and allowing the flap which travels in a path out of contact with the guide to rise, a very important step in the treatment (the separation of the flap I' from the body I) of the envelop is attained.

H is a roller (I have in my experiments used hardwood) turning freely on a sufficiently stout horizontal pin A^4 , which lies over the body of the envelop and holds it down still more effectually during the lifting and after the flap has been lifted.

M is a roller turning loosely on a rigid vertical pin A^5 , which extends downward from a sufficiently stout horizontal arm A^6 , reaching over the series of platforms. The surface of this roller is covered with felt or analogous material adapted to apply a small quantity of water uniformly over the gummed flaps as they are successively carried past it by the motion of the machine and gently compressed between this roller and the adjacent face of the side pieces.

A^7 is a horizontal strip of board or other material held on edge and extending along the side of the machine adjacent to the path of the platforms in the upper portion of their traverse.

A^8 is a cam-piece screwed or otherwise secured on the inner face of this portion A^7 . When the crank B^2 is turned and the endless belt D set in motion, the several platforms are carried successively along over the horizontal table A' , and the several side pieces G are allowed to stand each in an inclined position permitted by the distance of the board A^7 .

The several platforms and their side pieces are combined in sets of three, each set being similar to the others, and a description of one set will suffice for all. The side pieces of each set are engaged together by a pin G' in the foremost extending rearward and being received in a corresponding but somewhat larger recess g' in the next succeeding side piece. This recess is open at the back. The second side piece in each set is provided with a corresponding pin correspondingly marked, ex-

tending rearward and engaging in a corresponding recess g' in the rear side piece of the set. There are no means of engagement between the rearmost of the set and the next set except through the belt D.

When in the traversing of the belt and the several platforms and side pieces the foremost side piece of a set strikes the oblique front edge of the cam A^8 , it compels this front side piece to turn rapidly into the upright position, and by means of the pins G' , engaging the first piece with the second and the second with the third, all the side pieces G of that set are correspondingly lifted into the upright position.

$E^2 E^2$, &c., are gages. They may be simply smooth pins set in each platform E in the position represented near the axis of the hinges F. Experience may determine with different sizes and materials of envelops how these gages should be set. My experiments indicate that for ordinary work they should be about a quarter of an inch from the line traversed by the offsets e.

The attendant supplies the previously-filled envelops by laying them successively face downward upon the series of platforms E and thrusting each beyond the offset line e until its edge strikes the gages E^2 . In this position the envelop is carried forward, its body being held down nearly or quite in contact with the upper faces of the several platforms E, and the series of three side pieces are forcibly turned on their hinges F and caused to assume the upright instead of the inclined position.

This movement by bringing the edges G^2 forcibly down upon the overhanging edge of the envelop forces that edge downward into a vertical position, and the flap I' of the envelop being free and having some stiffness rises into a correspondingly vertical or nearly vertical position; but the main body I of the envelop being held down by the guide A^3 and roller H remains in very nearly the flat position it had before. Now the body of the envelop remaining flat, as before, while the flap I' extends upward

nearly or quite at right angles to the body the envelop, with its load, is carried past the wetting-roller M, which latter presses gently against the previously-gummed inner face of the flap I' and gives it the desired thin evenly-distributed coating of water. So soon as this face of the flap has been thus uniformly dampened by its passage between the roller M and the faces of the adjacent side pieces G the body I of the envelop which has been previously held down is allowed to rise. The resilience of the sharply-folded portion I² may not be sufficient to lift it. I provide an inclined lifter A⁹, which extends down nearly into contact with the upper surfaces of the several platforms E and is, furthermore, provided with a plow-point A¹⁰, which extends farther downward and is received in the groove e'. The offset e of the platforms E continues with the

side pieces G to maintain a firm grip on the sharply-bent edge of the envelop, so that the envelop is certain to continue moving forward, and the plow A¹⁰ and the adjacent inclined surface A⁹ promptly lift the body of the envelop into the upright position in contact with the wetted flap. Thus conditioned, the envelop passes an upright roller T, which is loosely mounted on a rigid pin A¹¹, extending downward from an extension of the lifter A⁹. The wetted flap stands upright, firmly supported by the correspondingly-traversing faces of the side pieces G. The surface of this roller T should be elastic. It exerts sufficient force against the body of the envelop to press it against the wetted flap and insure an effective contact over the whole surface. My experiments indicate that when the machine is run at ordinary speed the wetting softens and renders adhesive the whole surface of the coating of gum on the envelop. After being subjected to this final compression the side pieces are released one by one as they successively escape from the cam A⁸ and are allowed to assume their previous inclined positions. A¹³ is an inclined deflector which stands in a position to insure that the envelop shall be detached. A¹² is a piece attached to A¹³ arranged to insure that the side pieces shall be inclined. These acts liberate the now completely-sealed envelop, and it falls by gravity and is led away by a spout. (Not shown.)

The machine so far as yet described may be used with some success, care being taken to supply the moisture at short intervals by hand to the soft coating of the wetting-roller M. In such case the water may be applied by a camel's-hair brush, applying it mainly at the upper edge and allowing it to be distributed by the natural tendency of the water to spread under such circumstances aided by the gravity of the water. I have devised means for applying the water automatically with provisions for adjusting it as may be required by the thickness and quality of the paper and of the gum coating thereon, and especially by the hygrometric condition of the atmosphere for the time being.

A¹⁴ (see Figs. 1 and 3) is a tank, which may be much larger than shown, kept supplied with water and delivering it through a small passage controlled by any convenient device, as a cock or simply a tapering plug K. (Shown in dotted lines in Fig. 3.) The water descends from the tank A¹⁴ through this controllable passage a¹⁴ and is distributed on a short upright roller L, which turns loosely on the pin A¹⁵ and is provided with a soft water-retaining surface, as felt. The turning of the shaft B induces the continuous forward motion of the side pieces G. The friction of these side pieces causes the revolutions of the properly-dampened roller M, and the revolution of the latter acts frictionally on the feeding-roller

L, which latter is kept liberally wetted. This short roller being sufficiently wetted insures the proper moistening of the upper portion of the wetting-roller M. This is the part which treats the extreme rounded edge of the flap. The remainder of the roller is certain to be fairly wetted by the diffusion of the water aided by gravity. A¹⁶ is a broad inclined spout which is presented below and arranged to contact lightly with the lower edge of the wet surface of this roller L and lead harmlessly away the excess of water. It is well to adjust the controlling means K so that a slight surplus of water will descend upon the feed-roller.

P is a wiping-brush, or it may be a bunch of folded fabric or other convenient material, which may be removed and fresh substituted from time to time, the function of which is to wipe the working faces of the side pieces G during their return passage under the table A'.

The provisions shown make it easy to keep the feeding-roller L at a certain condition with regard to its wetness—a condition a little in excess of saturation—one in which no more water can be carried on the roller, because any excess which is supplied has opportunity to drain away. I provide for giving from this roller the required lesser degree of wetness by making the feeding-roller shorter and applying only to the upper half of the wetting-roller and also by making only a portion of the surface of the feeding-roller receptive. A preferable condition in this regard is to apply the soft water-holding surface material in the form of a screw-thread L'. The width of the screw-threads may bear any desired ratio to the width of the ineffective spaces between. Practice may determine in special cases. If the feeding-roller L has a screw-thread L' of felt, covering only about half its surface, the other half being the ineffective spaces between the threads, the water supplied to the wetting-roller M will serve successfully under ordinary conditions.

I have shown slots g at the lower edge of the folded metal which constitutes each side piece G, arranged to loosely receive the corresponding gage E². This allows the gages to be adjusted inward or outward, which can usually be done by simply bending, and prevents the gages from interfering with the elastic action of the side pieces.

Modifications may be made without departing from the principle or sacrificing the advantages of the invention. The platforms E may be narrower—that is to say, they may have less extension in the direction of the length of their traverse, using a correspondingly greater number. It is desirable to equip each machine so that it may be used with a considerable range of lengths and also of widths of the envelops. It is easy to proportion one machine to treat all the ordinary

sizes of envelopes for mailing letters and circulars which are to be sealed as letters. Very large envelopes should have a specially-adapted machine.

5 Instead of mounting the pressing-roller T on the same arm A⁹ which serves as a lifter for the body of the envelope there may be a separate arm provided to carry the roller.

There may be several of the wetting-rollers 10 M and several of the pressing-rollers T arranged to treat successively the passing envelopes.

It is well to make the feeding-roller L not only with its surfaces screw-threaded, so as to 15 present considerably less than its full surface to impart water to the wetting-roller M, but also to have it sufficiently different in diameter from the wetting-roller to present the wetting-surfaces of small area in new places 20 every time they come in contact with the less wetted surface of the wetting-roller. I have shown the lower end of the feeding-roller contracted in diameter and esteem such construction preferable; but this and other details 25 of the work may be varied within wide limits.

I claim as my invention—

1. A machine for closing and sealing envelopes comprising an endless belt and means for 30 moving it, small rigid platforms fixed thereto and moved therewith, adapted to receive the envelopes and carry them along therewith, hinged side pieces carried with such platforms and provisions for opening the envelope moistening the gummed surface of the flap, closing the envelope and pressing the flap firmly upon the body, combined substantially as herein specified.

2. In a machine for closing and sealing envelopes, an endless belt and means for moving 40 it, small rigid platforms fixed thereto and moved therewith adapted to receive the envelopes and carry them along therewith, hinged side pieces carried with such platforms and provisions by the offset e on the platforms and the movement of the side pieces past such offset for deflecting a portion of the envelope so as to induce a rise of the flap, in combination with each other and with means for preventing 45 the rising of the body of the envelope thereby insuring the open condition of the envelope ready for the succeeding operations, all substantially as herein specified.

3. In a machine for closing and sealing envelopes, an endless belt and means for moving 55 it, small rigid platforms fixed thereto and moved therewith adapted to receive the envelopes and carry them along therewith, hinged side pieces carried with such platforms and provisions by the offset e on the platforms and the movement of the side pieces past such offset for deflecting a portion of the envelope so as to induce a rise of the flap, in combination with each other and with means for prevent-

ing the rising of the body of the envelope, and means M for moistening the gummed inner face of the flap while thus held open, all substantially as herein specified.

4. In a machine for closing and sealing envelopes, an endless belt and means for moving 70 it, small rigid platforms fixed thereto and moved therewith adapted to receive the envelopes and carry them along therewith, hinged side pieces carried with such platforms and provisions by the offset e on the platforms and the movement of the side pieces past such offset for deflecting a portion of the envelope so as to induce a rise of the flap, in combination with each other and with means for preventing 75 the rising of the body of the envelope, and means M for moistening the gummed inner face of the flap while thus held open, and provisions for subsequently raising the envelope-body into contact with the so-moistened flap and pressing the surfaces firmly together, 80 all substantially as herein specified.

5. In a machine for closing and sealing envelopes, an endless belt and means for moving 85 it, small rigid platforms fixed thereto and moved therewith adapted to receive the envelopes and carry them along therewith, hinged side pieces carried with such platforms and provisions by the offset e on the platforms and the movement of the side pieces past such offset for deflecting a portion of the envelope so 90 as to induce a rise of the flap, in combination with each other and with means for preventing the rising of the body of the envelope, and means M for moistening the gummed inner face of the flap while thus held open, and provisions for subsequently raising the envelope-body into contact with the so-moistened flap and pressing the surfaces firmly together, 95 all substantially as herein specified.

6. A machine for closing and sealing envelopes comprising an endless belt and means for moving it, small rigid platforms fixed 100 thereto and moved therewith adapted to receive the envelopes and carry them along therewith, hinged side pieces carried with such platforms, and provisions by the offset e on the platforms and the movement of the side pieces past such offset for deflecting a portion of the envelope so as to induce a rise of the flap, in combination with the tank A¹⁴, discharge-passage a¹⁴, wetting-roller M, and controlling means K for regulating at will the supply of water thereto, all substantially as herein specified.

7. A machine for closing and sealing envelopes comprising an endless belt and means for moving it, small rigid platforms fixed 110 thereto and moved therewith adapted to receive the envelopes and carry them along therewith, hinged side pieces carried with such

platforms, and provisions by the offset e on the platforms and the movement of the side pieces past such offset for deflecting a portion of the envelop so as to induce a rise of the flap, in combination with the tank A^4 , discharge-passage a^4 , wetting-roller M , and controlling means K for regulating at will the supply of water thereto, and with the drain-spout A^{15} and the feed-roller intermediately 5 between the supply-passage a^4 and the wet-

ting-roller, all arranged for joint operation substantially as herein specified.

In testimony that I claim the invention above set forth I affix my signature in presence of two witnesses.
